TROUSERS AND LIKE GARMENT

Isaac Gold, Hillsdale, Mich., assignor to Hillsdale Manufacturing Company, Hillsdale, Mich., a corporation of Michigan

Application December 20, 1933, Serial No. 703,178

3 Claims. (Cl. 2—237)

This invention relates to trousers and like garments, and has especial reference to an improved waist fitting garment of this sort.

It is well known that, in garments such as trousers and the like, tailoring and alteration is necessary to fit the waist of the garment to the waist of the wearer, and that if the waist portion of the garment is too large it has an unbecoming, ill-fitting appearance, and makes it difficult to hold the trousers in place around the waist of the wearer, particularly by means of a belt, whereas if the waist portion is too small it is accompanied by discomfort and hampers the freedom of the wearer.

15 The present invention has for one of its objects the provision of an improved waist construction which will fit the wearer snugly without tailoring or alteration to the waist size of the wearer, and which will yield about the waist of the wearer to give the wearer freedom and comfort without looseness about the waist of the garment.

Another and more specific object is the provision of elastic means secured internally to the waist portion of the garment at spaced locations and covered by the waist portion to provide a garment of pleasing appearance, and still more specifically the provision with such elastic means inside the waist of the garment of a waist construction between the locations of securement of the elastic means to the waist portion for allowing such waist portion to accommodate and adjust itself to the waist of the wearer under the action of the elastic means and without wrinkling or other unbecoming appearance about the waist of the garment.

35 Another and still more specific object is the provision of a waist-fitting garment having vents dividing the waist portion into parts with elastic means extending across the vents and secured internally to the parts of the waist portion on opposite sides of the vents and with the ends of the waist portion parts overlapping at the vents to allow the waist portion to be extended without opening the vents between the waist parts and exposing the elastic means therethrough.

40 Further objects and the advantages and details of the illustrated embodiment of the invention will appear from the following detailed description taken in connection with the accompanying drawing, in which:

Figure 1 is a fragmentary perspective view of a pair of trousers embodying the present invention;

Figure 2 is a fragmentary detail perspective view on a slightly larger scale than Figure 1;

55 Figure 3 is a fragmentary side elevation show-

ing the waist-fitting action at one side of the waist of the garment; and

Figure 4 is a fragmentary detail view showing another form of vent structure embodying the present invention.

Referring to the drawing, the trousers, designated in their entirety at 5, may be of the usual or any suitable or preferred material and of any usual or preferred construction modified according to the present invention as hereinafter described.

The main body of the trousers shown comprises the right and left leg portions 6 and 7, the usual side pockets 8, back pockets 9, and the usual small right front pocket 10. The left front section has the part or fly 12 adapted to be opened and closed and secured, when closed, to the opposite front section 13 by buttons 14. The lower ends of the leg portions 6 and 7 are broken away, but it is to be understood that they may be extended down and finished with or without cuffs, or they may be of knicker or bloomer form. The particular garment shown is provided with the usual side seams 15 and back seam 16, this particular garment being made up the right and left front sections and the back section secured together at the side seams 15 in the usual manner. The inner seams between the inner margins of the front sections and the back section are not shown.

30 The above described features are desirable and usual in garments of this sort, but it will be understood that these features are not essential and that modifications may be made therein as suitable or desired. And the leg portions of the 35 garment may be full length or short length, or of knicker, bloomer or other form as referred to above.

To the upper margins of the right and left front sections and back section a waist band 40 designated in its entirety at 18 is stitched or otherwise suitably secured at 20. This waist band 18 is preferably of the same material as the trousers, although it may be of another material as suitable or desired. It constitutes the 45 waist part, or at least a portion of the waist part, of the garment.

The waist band or waist portion 18 is divided at the open front of the garment and by vents 22, one at each of the opposite sides of the 50 garment, into a right front waist band portion 23, a left front waist band portion 24, and a back waist band portion 25, which back waist band portion 25 may be made up of right and left band portions stitched or otherwise secured 55

together at 26 at the back seam 16. The left front band portion 24 is of substantially the same length as the upper edge of the left front section of the garment and is stitched to the upper edge of this front section. Its front end terminates at the front edge of the fly 12 and is provided with buttonholes 28 for engagement with buttons 29 on the overlapping end of the right front band portion 23, which is of substantially the same length as the upper edge of the right front section, and is stitched to the upper edge of said section. The front end of the waist band portion 23 preferably terminates at the adjacent edge of the adjacent front section to which it is secured.

The lower edge of the rear waist band portion 25 is of substantially the same length as the upper edge of the back section of the trousers and is stitched along the line 29 to the upper edge of the back section. The side ends of the upper margin of the back section of the garment preferably overlap at 30 the side ends of the upper margins of the front sections and are stitched thereto at 34. The side end of the lower edge of each band 23 and 24 extends to the side end of the upper margin of the adjacent front section, and the lower edge of the side ends of the band 25 extend to the side ends of the upper margin of the back section, which results in the side ends of the band 25 overlapping the adjacent side ends of the bands 23 and 24 at the side vents 22 of the garment. The overlapping ends of the upper margins of the front and rear sections of the main body of the garment may be produced in any suitable or preferred manner. In the illustrated embodiment, the edges of these ends are merely continuations of the marginal edges secured together at the seams 15 and the extension of the inward bias of these marginal edges from the hip portion to the waist portion of the garment provides sufficient material for the overlap at 30.

To increase further the overlap of the ends of the bands at the side vents 22 the side ends of the bands 23 and 24 preferably terminate on a bias at 36 to provide a greater overlap at the top of the waist portion than at the bottom. The front ends of the band portion 25 may, likewise, terminate on a bias to give the upper margin of this band section a greater waistline dimension than the lower margin, but this is not necessary and, in the illustrated embodiment, these ends terminate substantially square or substantially as continuations of the seams 15. The band sections 23, 24 and 25 are provided with the usual looped belt straps 38. One of these belt straps 38 is preferably provided on each of the band sections 23 and 24 just forwardly of each of the vents 22, and the band section 25 is preferably provided with similar straps 38 rearwardly of these vents 22.

The elastic means for the waist of the garment comprises a pair of elastic bands 40, one extending across each of the side vents 22 and stitched internally to the waist band portions of the garment at its opposite ends at 42. These elastic bands 40 may consist of stretchable cloth material and rubber threads or bands woven or otherwise fabricated into the bands to give the same the desired elasticity. The waist portion of the trousers is preferably provided with the usual lining 45, and the bands 40 are preferably disposed internally of this lining and stitched to the respective waist band sections, one band 40 to the waist band sections 24 and 25, and the

other band 40 to the waist band sections 23 and 25, as shown. In the illustrated embodiment, the ends of the respective elastic bands 40 are folded under at 46 where they are stitched at 42 to the respective band sections of the garment. The rearward belt straps 38 on the forward sections of the garment and the forward belt straps on the rearward section of the garment may be disposed adjacent the stitching of the opposite ends of the flexible bands 40 to the respective 10 waist band sections of the garment.

In use, the elastic bands 40 make the garment waist-fitting and hold the waist portion of the garment snugly to the waist of the wearer without accurate tailoring or alteration of the waist 15 of the garment to fit the waist of the wearer and, at the same time, the bands 40 yield about the waist to give the wearer freedom and comfort without looseness about the waist of the garment. The side vents 22 constitute means between the 20 spaced locations of securement of the elastic bands for allowing these bands to hold the waist portion to the waist of the wearer and to yield about the waist without an unbecoming, ill-fitting appearance. And, as shown in Figure 3, 25 the overlapping ends of the waist band sections at the vents 22 allow for extension of the waist portion of the garment without exposing the elastic bands 40 which are covered and at all times concealed by the waist portion of the 30 garment.

In the embodiment of Figure 4, the right and left sides of the back section 50 of the garment are slit vertically from the upper marginal edge of the back section down toward the rear pockets, 35 one of which is shown at 51 just rearwardly of the side seams 52 which join the back section to the respective front sections 50'. The lower end of each of these slits terminates above the adjacent rear pocket 51, and a fold or pleat 53 continuing downwardly from the slit brings the rear marginal edge along the slit into forwardly overlapping relation with respect to the front marginal edge along the slit as shown at 54. The waist band sections 55 and 56 terminate at substantially the free edges of the front and back sections 50' and 50 along the opposite sides of the slit and are stitched to the upper margins of the front and back sections at 57. An insert 58, preferably comprising a strip of the same material as the main body portion of the garment is stitched at 59 to the free edge of the band section 55 and down to the adjacent edge of the back section 50 along the slit. At the lower end of the slit this insert strip 58 is folded up at 60 and the forward edges of the back section 50 and band section 56 are folded in at 61 along the slit and stitched at 62 to the forward edge of the unfolded portion of the insert 58. The insert 58, the upper ends of which terminate at the upper margins of the band sections 55 and 56, respectively, which upper ends may be suitably finished as desired, forms the overlap at the vent designated in its entirety at 62. The elastic band 63 extends across the vent 62 and is stitched or otherwise secured at its opposite ends at 64 to the band sections 55 and 56 inside the lining 65 within the band sections, as before.

While I have described the invention in connection with a pair of trousers, it is to be understood that the invention may be embodied in the waist band structures of skirts and all similar or equivalent garments as suitable or desired. And the invention is not to be limited to the precise details shown and described.

I claim:

1. In a garment of the class described, the combination of a waist portion provided with a slit therein, an insert secured to one edge of the garment along the slit in position projecting from said edge, said insert being folded up and secured to the opposite edge of the garment along the slit to produce an overlap at the slit, and an elastic band extending across the slit and secured internally to the garment on opposite sides of the slit.

2. In a garment of the class described, the combination of a waist portion provided with a slit therein, an insert secured to one edge of the garment along the slit in position projecting from said edge, said insert being folded up and secured to the opposite edge of the garment along the slit to produce an overlap at the slit, an elastic band

extending across the slit and secured internally to the garment on opposite sides of the slit, and a fold formed in the garment and continuing downwardly from the slit.

3. In a garment of the class described, a main body portion, a waist band along the top of said main body portion, said waist band having a slit extending downwardly therethrough, a fold formed in the body portion and extending downwardly from said slit, an insert secured to one edge of the waist band at the slit and extending downwardly to the bottom of the slit and folded upwardly and secured to the opposite edge of the waist band along the slit to produce an overlap of the waist band at the slit, and an elastic band secured internally to the waist band on opposite sides of the slit.

5

ISAAC GOLD.
